(57) ABSTRACT

A new *Chrysanthemum* plant named 'CIDZ0015' particularly distinguished by the intense red-purple ray floret color, medium green foliage, six weeks flowering response, small sized foliage, very compact growth habit and is very freely branching.

1 Drawing Sheet

1

Latin name of the genus and species of the plant claimed:
Chrysanthemum×morifolium.

Varietal denomination: 'CIDZ0015'.

BACKGROUND OF THE NEW PLANT

The present invention comprises a new *Chrysanthemum*, botanically known as *Chrysanthemum×morifolium*, and hereinafter referred to by the variety name 'CIDZ0015'.

'CIDZ0015' is a product of a planned breeding program. The new cultivar has intense red-purple ray floret color, medium green foliage, six weeks flowering response, small sized foliage, very compact growth habit and is very freely branching.

'CIDZ0015' originated from a hybridization made in April 2007 in a controlled breeding environment in Salinas, Calif. USA. The female parent was the proprietary plant designated 'YB-A1859', unpatented, with dark pink flowers and with more whorls of ray florets than 'CIDZ0015'.

The male parent of 'CIDZ0015' was an unpatented plant identified as 'YB-B1820' with red flowers and is a week slower to flower. The resultant seed was sown in October 2007 in Fort Myers, Fla. USA.

'CIDZ0015' was selected as one flowering plant within the progeny of the stated cross in March 2008 in a controlled environment in Fort Myers, Fla. USA.

The first act of asexual reproduction of 'CIDZ0015' was accomplished when vegetative cuttings were propagated from the initial selection in June 2008 in a controlled environment in Fort Myers, Fla. USA.

BRIEF SUMMARY OF INVENTION

Horticultural examination of plants grown from cuttings of the plant initiated in June 2008, and continuing thereafter, has demonstrated that the combination of characteristics as herein disclosed for 'CIDZ0015' are firmly fixed and are retained through successive generations of asexual reproduction.

2

'CIDZ0015' has not been observed under all possible environmental conditions. The phenotype may vary significantly with variations in environment such as temperature, light intensity and day length.

5 A Plant Breeder's Right for this cultivar was applied for in Canada on Aug. 17, 2010 (10-7073). 'CIDZ0015' has not been made publicly available more than one year prior to the filing of this application.

The following traits have been repeatedly observed and are 10 determined to be basic characteristics of the new variety. The combination of these characteristics distinguishes this *Chrysanthemum* as a new and distinct variety.

BRIEF DESCRIPTION OF THE PHOTOGRAPHS

15 The accompanying photographic drawing shows typical flower and foliage characteristics of 'CIDZ0015' with colors being as true as possible with an illustration of this type.

The photographic drawing shows a flowering potted plant 20 of the new variety and a close-up of the flowers.

DETAILED BOTANICAL DESCRIPTION

The plant descriptions, measurements and aforementioned 25 photographs were taken in Gilroy, Calif. in early May 2011 under natural light. These plants were propagated and grown in Nipomo, Calif. and shipped to Gilroy, Calif. for the data collection and photographs. These plants were approximately 11 weeks of age; grown with three plants together in a five 30 inch bulb pan under greenhouse trial conditions.

Color references are made to The Royal Horticultural Society Colour Chart (R.H.S.) 2001.

TABLE 1

35 DIFFERENCES BETWEEN THE NEW VARIETY 'CIDZ0015' AND A MOST SIMILAR COMMERCIAL VARIETY		
	'CIDZ0015'	'Yomistique' (U.S. Plant Pat. No. 17,412)
40	Ray floret color: Quantity of disc florets:	More red-purple About 150
		More purple About 120

TABLE 1-continued

DIFFERENCES BETWEEN THE NEW VARIETY 'CIDZ0015' AND A MOST SIMILAR COMMERCIAL VARIETY		
		'Yomistique' (U.S. Plant Pat. No. 17,412)
Foliage color, upper surface:	Less yellow-green	More yellow-green
Plant:		
<i>Form, growth and habit.</i> —Herbaceous pot type, stems upright and outwardly spreading, freely branching.		
<i>Plant height.</i> —11.0-12.0 cm.		
<i>Plant height (inflorescence included).</i> —16.0-17.0 cm.		
<i>Plant width.</i> —12.0-13.0 cm.		
Roots:		
<i>Number of days to initiate roots.</i> —About 4 days at about 22 degrees C.		
<i>Number of days to produce a rooted cutting.</i> —About 10 days at 22 degrees C.		
<i>Type.</i> —Fine, fibrous, free branching.		
<i>Color.</i> —RHS N155B but whiter.		
Foliage:		
<i>Arrangement.</i> —Alternate, simple.		
<i>Immature, leaf color, upper surface.</i> —RHS 137A but darker.		
<i>Lower surface.</i> —RHS 137B.		
<i>Mature, leaf color, upper surface.</i> —RHS 137A.		
<i>Lower surface.</i> —RHS 137C.		
<i>Length.</i> —4.3-5.0 cm.		
<i>Width.</i> —3.5-4.5 cm.		
<i>Shape.</i> —Ovate.		
<i>Base shape.</i> —Attenuate.		
<i>Apex shape.</i> —Mucronulate.		
<i>Margin.</i> —Lobed; irregularly serrate.		
<i>Texture, upper surface.</i> —Bifid T-shaped hairs.		
<i>Lower surface.</i> —Bifid T-shaped hairs.		
<i>Color of veins, upper surface.</i> —RHS 144B.		
<i>Color of veins, lower surface.</i> —RHS 144B.		
<i>Petiole color.</i> —RHS 144B with darker margins.		
<i>Length.</i> —1.0-1.3 cm.		
<i>Diameter.</i> —0.3 cm.		
<i>Texture.</i> —Bifid T-shaped hairs.		
Stem:		
<i>Quantity of main branches per plant.</i> —3-4.		
<i>Color of stem.</i> —RHS 137B but appears lighter due to hairs.		
<i>Length of stem.</i> —8.0-10.0 cm.		
<i>Diameter.</i> —3.0-4.0 cm.		
<i>Length of internodes.</i> —1.5-2.0 cm.		
<i>Texture.</i> —Bifid T-shaped hairs.		
<i>Color of peduncle.</i> —RHS 137B but appears lighter due to hairs.		
<i>Length of peduncle.</i> —1.7-1.8 cm.		
<i>Peduncle diameter.</i> —0.2 cm.		
<i>Texture.</i> —Bifid T-shaped hairs.		
Inflorescence:		
<i>Type.</i> —Compositae type, solitary inflorescences, daisy- type, borne terminally above foliage, ray florets arranged acropetally on a capitulum.		
<i>Quantity of short days to flowering (response time).</i> — About 6 weeks.		
<i>Quantity of inflorescences per plant.</i> —50-55.		

		<i>Lastingness of individual blooms on the plant.</i> —About 4 weeks.
		<i>Fragrance.</i> —Slightly spicy.
		<i>Bud (just when opening/showing color).</i>
5		<i>Color.</i> —Closest to RHS 70A but with a little more red.
		<i>Length.</i> —0.5-0.7 cm.
		<i>Width.</i> —0.8-0.9 cm.
		<i>Shape.</i> —Oblate.
		<i>Immature inflorescence:</i>
10		<i>Diameter.</i> —2.3-2.5 cm.
		<i>Color of ray florets, upper surface.</i> —Closest to RHS 71A.
		<i>Lower surface.</i> —Between RHS N74C and N74D.
		<i>Mature inflorescence:</i>
15		<i>Diameter.</i> —3.5-4.0 cm.
		<i>Depth.</i> —1.0 cm.
		<i>Total diameter of disc.</i> —1.5 cm.
		<i>Receptacle height.</i> —0.3 cm.
		<i>Receptacle diameter.</i> —0.35-0.4 cm.
		<i>Ray florets:</i>
		<i>Average quantity of florets.</i> —21-25 in 1-2 whorls.
		<i>Color of florets, upper surface.</i> —Closest to RHS 70B but a more silvery-grey hue, with slightly darker apex.
		<i>Lower surface.</i> —Closest to RHS 70B to 70C.
		<i>Length.</i> —1.7-1.9 cm.
		<i>Width.</i> —0.55-0.7 cm.
		<i>Shape.</i> —Elliptical.
		<i>Apex shape.</i> —Irregularly emarginate.
		<i>Margin.</i> —Entire.
		<i>Texture, upper surface.</i> —Papillose.
		<i>Lower surface.</i> —Papillose.
		<i>Disc florets:</i>
25		<i>Average quantity of florets.</i> —Approximately 150.
		<i>Color of florets.</i> —RHS 1C with RHS 6A apex.
		<i>Length.</i> —0.4 cm.
		<i>Width.</i> —0.1 cm.
		<i>Shape.</i> —Tubular, elongated.
		<i>Apex shape.</i> —Acute, 5 pointed.
		<i>Phyllaries:</i>
30		<i>Quantity.</i> —18-20.
		<i>Color, upper surface.</i> —RHS 137B.
		<i>Lower surface.</i> —RHS 137B but appears lighter due to hairs.
		<i>Length.</i> —0.4-0.5 cm.
		<i>Width.</i> —0.1-0.2 cm.
		<i>Shape.</i> —Lanceolate.
		<i>Apex shape.</i> —Obtuse.
		<i>Base.</i> —Fused.
		<i>Margins.</i> —Entire; papery.
		<i>Texture, upper surface.</i> —Glabrous.
		<i>Lower surface.</i> —Bifid T-shaped hairs.
		<i>Reproductive organs:</i>
35		<i>Pistil.</i> —1.
		<i>Found on both florets.</i> —Yes.
		<i>Length.</i> —0.4 cm.
		<i>Style color.</i> —RHS 1C.
		<i>Style length.</i> —0.5 cm.
		<i>Stigma color.</i> —RHS 7A.
		<i>Stigma shape.</i> —Bi-parted.
		<i>Ovary color.</i> —Not observed; ovary too immature to observe any color due to maturing with pollination.
		<i>Stamens.</i> —1.
		<i>Found on only disc florets.</i> —Yes; but no healthy stamens were observed on these plants at the time that this data was collected.

US PP22,747 P2

5

Color of filaments.—Not observed.
Length filaments.—Not observed.
Anther color.—Not observed.
Anther length.—Not observed.
Anther shape.—Not observed.
Color of pollen.—Not observed.
Pollen amount.—Not observed.
Fertility/seed set.—Has not been observed on this hybrid.

6

Disease/pest resistance: Disease/pest resistance has not been observed on this hybrid.

What is claimed is:

5 1. A new and distinct variety of *Chrysanthemum* plant named 'CIDZ0015' substantially as illustrated and described herein.
